IRONING BOARD LEG MOUNTING

Lucius L. Daugherty, Jr., Jacksonville, Fla.

Application November 27, 1945, Serial No. 631,144

11 Claims. (Cl. 38—117)

1

This invention relates to an ironing board, and more particularly to that class of ironing board having a pair of rear legs and a composite forward leg with suitable bracing means provided between the legs. More particularly, the invention relates to that type of ironing board in which the rear legs are adapted for swinging movement on oblique pivots so as to spread at their lower or outer ends as they swing into extended relation to the board.

It is the object of my invention to provide an ironing board of the particular class in which the legs will be extremely well braced relatively to the board so as to contribute a rigid ironing board of the class so highly desired by the consuming public. As a feature of my invention, each of the rear legs is adapted to be braced relatively to the ironing board by brace levers that swing with the legs during movement of the legs to extended position, this swinging movement being adapted to bring the brace levers into a position so that they extend angularly upwardly transversely of the board from the legs to the board. This arrangement contributes extreme rigidity as will become more apparent after a description of the invention.

More particularly, it is a feature of the invention that the brace levers form an X member with the upper ends of the brace levers braced directly against the ironing board in a position transversely displaced from the pivot axis of the legs. More particularly, it is a feature of the invention that the brace levers are secured with their outer ends to the legs and are then crossed with their inner ends secured to link members that are adapted to move against the face of the board and thereby support and brace the brace levers. Even more particularly, it is a feature of the invention that the links are adapted for pivotal movement so as to spread the outer ends of the brace levers forming the X, whereby to hold the legs braced in their spread position.

I have thus outlined rather broadly the more important features of my invention, in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized by those skilled in the art as a basis for the designing of other structures for carrying out the several pur-

2

poses of my invention. It is important therefore that the claims to be granted me shall be of sufficient breadth to prevent the appropriation of my invention by those skilled in the art.

Referring now to the drawings, Fig. 1 is a perspective view showing the ironing board with the legs in extended relation; that is in supporting relation to the board. Fig. 2 is an enlarged view of parts of the ironing board assembly looking at Fig. 1 in the direction of the arrows 2—2 of Fig. 1. Fig. 3 is a view taken along lines 3—3 of Fig. 2. Fig. 4 is a view looking at the bottom of the board and showing the legs and linkage folded thereagainst. Fig. 5 is a view taken along lines 5—5 of Fig. 4. Fig. 6 is an end view taken substantially along the same lines as Fig. 3, but showing the brace levers and links in a position when the legs are intermediate the folded position of Fig. 4 and the fully extended position of Fig. 1. Fig. 7 is an elevation of certain of the parts of Fig. 6 illustrating the construction of the mounting means for the links. Fig. 8 is an exploded view of the links and the means supporting the links for movement relatively to the board.

Referring now more particularly to the drawings, the ironing board of my invention is designated by reference numeral 10, and supports thereon a forward leg pivoting bracket 11 and a rear leg pivoting bracket 12. The forward bracket 11 has pivoted thereto at 13 and 14 a pair of leg struts 15 that form what I term a composite front leg 16, all as those skilled in the art will appreciate.

A toggle bar 17 is pivoted at 18 to a third bracket 19, supported by the board 10, the other end of the toggle bar being pivoted at 20 to a bifurcated lever 21 pivoted at 22 and 23 to the leg struts 15 of the composite leg 16. A limit stop 24 is secured to the toggle bar 17 and is adapted to abut the metal of the bifurcated lever 21 when the forward composite leg 16 is extended to the position of Fig. 1 and the full line position of Fig. 2. It will be noted that when the composite leg 16 moves to its full line position of Fig. 2 from its dotted line position of that same figure, the toggle bar 17 is moved beyond dead center. In other words, the pivot axis 20 is moved beyond the straight line connecting the pivots 22, 23 and the pivot 18. Therefore, in the full line position of the composite leg 16 in Fig. 2, any tendency of the leg to move to its dotted line position will be resisted by the bifurcated lever 21 lying against the surface of the limit stop 24. Therefore, it will be impossible for the composite leg 16 to be moved to its position of Fig. 4. In

order to move the leg 16 to its position of Fig. 4 it is necessary to break the toggle that exists between the toggle bar 17 and the bifurcated lever 21. This is accomplished by moving the toggle bar 17 to its dotted line position of Fig. 2, after which the swinging of the composite leg 16 in a clockwise direction about its pivots 13 will bring the forward leg 16 into its folded relation to the board illustrated in Figs. 4 and 5.

Pivoted to the rear leg bracket 12 on oblique pivots 25 are legs 26, these legs being adapted to swing from the position of Fig. 4 to their extended and spread position of Figs. 1 and 3. A pair of rods 27 are pivoted at 28 to the legs 26, the other ends of the rods 27 being pivotally secured on a bolt 29 that is adapted to secure together the leg struts 15 of the composite forward leg 16. The use of the rods 27 for bracing the legs relatively to one another and for simultaneous movement of the legs into and out of extended position will, of course, be quite apparent to those skilled in the art.

Secured to each leg 26 is a small bracket 30, and pivoted to each bracket 30 about a rivet 31 is what I term a brace lever 32. That end of each brace lever 32 that is pivoted to a bracket 30 on the axis of a rivet 31 I term the outer end of the brace lever. The pair of brace levers 32 are adapted to cross, and where they cross they are pivoted to one another about a rivet 33 that is parallel to the rivets 31. At that end of each brace lever 32 opposite its outer end, and hereinafter called the inner end, I pivot what I term a link 34. Each link 34 is pivoted to its brace lever 32 by means of a rivet 35, the pair of rivets 35 being parallel to rivets 31 and 33. The two links 34 are then pivoted to one another through a rivet 36 that is parallel to the rivets 31, 33, and 35 already indicated.

It is now quite obvious that swinging movement of the rear legs 26 will effect a spreading of the brace levers 32 because of their X relationship best illustrated in Fig. 4, and because of the arrangement of the links 34. This takes place as the brace levers swing bodily with the legs 26. Through means presently to be described, it will be shown how the links 34 are adapted also to be spread into a position wherein they lie along a straight line that is transverse of the board.

Thus, as best illustrated in Figs. 5 to 8, there is secured to the board an L-shaped bracket 37 and pivoted to this bracket on a pivot axis 38 is a short link 39. Pivoted to this short link 39 on an axis 40 is what I term a pivot member 41. This pivot member 41 carries the rivet 36 to which are pivoted the links 34. Because of the particular arrangement, a swinging movement of the legs from the position of Fig. 4 toward the extended position of Fig. 1 will bring the brace levers 32 and links 34 into the intermediate position of Figs. 6 and 7. In that position of the parts it will be noted that the links 34 have already moved into a position wherein they are about to assume a straight line relationship with the X formed by the brace levers already somewhat spread.

The further swinging of the legs 26 will cause a lug 34a of one of the links 34 to ride into a notch 34b of the other link 34 as the legs assume their fully extended and spread position of Figs. 1 and 3. It is in Fig. 3 that the straight line relationship of the links 34 is best illustrated. The movement of the links into this straight line position was made possible by their pivotal relationship relatively to the pivot member 41. Be-

cause of the presence of the short link 39 pivoted to the bracket 37, the links 34 not only move pivotally relatively to one another, but are swung bodily with the brace levers 32 and the legs 26 into a position juxtaposed or against the bottom of the board 10.

Preferably, the ends 32a of the brace levers 32 are cut angularly so that said surfaces 32a may lie physically against the board, but actually,

10 it is possible to obtain the same effect by having the links 34 lie against the board and with the brace levers 32 braced relatively to the board through the intermediary of the pivot rivets 35, all as will be apparent to those skilled in the art.

15 In dotted lines in Fig. 8, extensions 34c are shown on links 34, these extensions being adapted to lie against the board where the links 34 rather than the ends 32a of brace levers 32, impinge against the board.

20 Because of the particular relationship of the parts, it will be seen that the legs 26 in the position of Fig. 1 are braced absolutely against collapse laterally or transversely of the board 10, this being very effective because of the X relationship of the brace levers 32 and their positioning in braced relationship against the board itself or through the intermediary of links 34. It will also be noted that the brace levers are incapable of movement relatively to the board transversely

25 thereof because of the arrangement of the links 34. Of course, any swinging movement of the legs 26 clockwise on their pivots 25 from Fig. 1 is impossible because of the connection between the said legs and the forward composite leg 16.

30 Swinging movement in a counter-clockwise direction of the legs is, of course, prevented by the bracing effect of the brace levers 32, the said brace levers preventing also any transverse yielding of the said legs as already set forth.

35 40 I believe the construction, utility, and operation of my invention will now be apparent to those skilled in the art.

I now claim:

1. In an ironing board, a pair of legs, means 45 pivoting said legs relatively to said board on pivot axes substantially transverse of said board for swinging movement longitudinally of the board into an extended position and into a retracted position against the board, a brace lever pivoted at its outer end to each of said legs for swinging movement therewith, said brace levers crossing one another to form an X, means pivoting said brace levers to one another where they cross, a link pivoted to the inner end of each of said 50 brace levers, mounting means mounting said links relatively to the board for swinging movement whereby the brace levers will swing with said legs at one end and with said links at their other ends, said links swinging on said mounting means toward the board when said legs are extended and with said brace levers thereby braced between said board and said legs.

2. In an ironing board, a pair of legs, means 55 pivoting said legs relatively to said board on pivot axes substantially transverse of said board for swinging movement longitudinally of the board into an extended position and into a retracted position against the board, a brace lever pivoted at its outer end to each of said legs for swinging movement therewith, said brace levers crossing one another to form an X, means pivoting said 60 brace levers to one another where they cross, a link pivoted to the inner end of each of said brace levers, mounting means mounting said links relatively to the board for swinging movement

whereby the brace levers will swing with said legs at one end and with said links at their other ends, means whereby said links pivot relatively to said mounting means so that their pivots with said levers may assume a line position parallel to said board, said links swinging on said mounting means and pivoting relatively thereto toward the board when said legs are extended and with said brace levers thereby braced between said board and said legs.

3. In an ironing board, a pair of legs, means pivoting said legs relatively to said board on pivot axes substantially transverse of said board for swinging movement longitudinally of the board into an extended position and into a retracted position against the board, a brace lever pivoted at its outer end to each of said legs for swinging movement therewith, said brace levers crossing one another to form an X, means pivoting said brace levers to one another where they cross, a link pivoted to the inner end of each of said brace levers, mounting means mounting said links relatively to the board for swinging movement substantially parallel to the direction of swinging of said leg whereby the brace levers will swing with said legs at one end and with said links at their other ends, said swinging movement bringing said brace levers into a position wherein they are braced between said board and said legs and are held by said links against movement transverse of said board.

4. In an ironing board, a pair of legs, means pivoting said legs relatively to said board on pivot axes substantially transverse of said board for swinging movement longitudinally of the board into an extended position and into a retracted position against the board, a brace lever pivoted at its outer end to each of said legs for swinging movement therewith, said brace levers crossing one another to form an X, means pivoting said brace levers to one another where they cross, a link pivoted to the other end of each of said brace levers, a pivot member to which said links are pivoted, means mounting said pivot member for swinging movement on said board substantially parallel to the swinging movement of said legs, the simultaneous swinging movement of said legs and pivot member acting to swing and pivot said brace levers and links whereby said legs are extended with said legs braced between the legs and the board and said links holding said brace levers against movement from bracing position.

5. In an ironing board, a pair of legs, means pivoting said legs relatively to said board on pivot axes substantially transverse of said board for swinging movement longitudinally of the board into an extended position and into a retracted position against the board, a brace lever pivoted at its outer end to each of said legs on an axis substantially perpendicular to the pivot axis of said legs whereby said brace levers swing bodily with said legs, said brace levers crossing one another and pivoted to one another at the point of crossing, a pair of links pivoted to each other and pivoted at their outer ends to the inner ends of said brace levers, all of said pivots being substantially parallel to the pivots between said brace levers and legs, a pivot member supporting the pivot between said two links, means mounting said pivot member for swinging movement on said board substantially parallel to the swinging movement of said legs, the simultaneous swinging movement of said legs and pivot member acting to extend said legs from said board and to bring said links against the board and

transversely thereof with said brace levers in X relation and extending between said links and legs in bracing position.

6. In an ironing board, a pair of legs, means pivoting said legs relatively to said board on pivot axes substantially transverse of said board for swinging movement longitudinally of the board into an extended position and into a retracted position against the board, a brace lever pivoted at its outer end to each of said legs on an axis substantially perpendicular to the pivot axis of said legs whereby said brace levers swing bodily with said legs, said brace levers crossing one another and pivoted to one another at the point of crossing, a pair of links pivoted at one end thereof to one another and at their opposed ends to the inner ends of said brace levers, all of said pivots being substantially parallel to the pivots between said brace levers and legs, and means pivoting said links on a horizontal axis transverse of said board for movement bodily with said legs and brace levers while said brace levers and links pivot to one another, whereby to bring said links into a position transverse of said board with said brace levers braced between said legs and board while held by said links against transverse movement relatively to said board.

7. In an ironing board, a pair of legs, means pivoting said legs relatively to said board on pivot axes substantially transverse of said board for swinging movement longitudinally of the board into an extended spread position and into a retracted position against the board, a brace lever pivoted at its outer end to each of said legs on an axis substantially perpendicular to the pivot axis of said legs whereby said brace levers swing bodily with said legs, said brace levers crossing one another and pivoted to one another at the point of crossing, a pair of links pivoted at one end thereof to one another and at their opposite ends to the inner ends of said brace levers, all of said pivots being substantially parallel to the pivots between said brace levers and legs, a bracket on said board, a short link pivoted to said bracket for movement on a horizontal axis transverse of said board, a pivot member supporting the pivot between the two links, and said pivot member pivoting on said short link and with said short link relatively to said bracket for swinging said links bodily with said legs and brace levers while said links pivot relatively to one another, whereby to bring said links into a position transverse of said board with said brace levers braced between said legs and board while held by said links against transverse movement relatively to said board.

8. In an ironing board, a pair of legs, means pivoting said legs relatively to said board on pivot axes substantially transverse of said board for swinging movement longitudinally of the board into an extended position and into a retracted position against the board, a brace lever pivoted at its outer end to each of said legs for swinging movement therewith, said brace levers crossing one another to form an X, means pivoting said brace levers to one another where they cross, a link pivoted to the inner end of each of said brace levers, mounting means mounting said links relatively to the board for swinging movement whereby the brace levers will swing with said legs at one end and with said links at their other ends, said links swinging on said mounting means to bring the inner ends of said brace levers against the board when said legs are extended and with

said brace levers thereby braced between said board and said legs.

9. In an ironing board, a pair of legs, means pivoting said legs relatively to said board on pivot axes substantially transverse of said board for swinging movement longitudinally of the board into an extended position and into a retracted position against the board, a brace lever pivoted at its outer end to each of said legs on an axis substantially perpendicular to the pivot axis of 10 said legs whereby said brace levers swing bodily with said legs, said brace levers crossing one another and pivoted to one another at the point of crossing, a pair of links pivoted to each other and pivoted at their outer ends to the inner ends 15 of said brace levers, all of said pivots being substantially parallel to the pivots between said brace levers and legs, a pivot member supporting the pivot between said two links, means mounting said pivot member for swinging movement on 20 said board substantially parallel to the swinging movement of said legs, the simultaneous swinging movement of said legs and pivot member acting to extend said legs from said board and to bring said links into juxtaposition to said 25 board and transversely thereof with said brace levers in X relation and extending between said links and legs in bracing position with the inner ends of said brace levers abutting the board.

10. In an ironing board, a pair of legs, means pivoting said legs relatively to said board on pivot axes substantially transverse of said board for swinging movement longitudinally of the board into an extended position and into a retracted position against the board, a brace lever 30 pivoted at its outer end to each of said legs on an axis substantially perpendicular to the pivot axes of said legs whereby said brace levers swing bodily with said legs, said brace levers crossing one another and pivoted to one another at the point of crossing, a pair of links pivoted at one 35 end thereof to one another and at their opposed ends to the inner ends of said brace levers, all of said pivots being substantially parallel to the pivots between said brace levers and legs, and means pivoting said links on a horizontal axis 40 transverse of said board for movement bodily with said legs and brace levers while said brace levers and links pivot to one another, whereby to 45

bring said links into a position transverse of said board with the inner ends of said brace levers in contact with the board while held by said links against transverse movement relatively to said board.

11. In a ironing board, a pair of legs, means pivoting said legs relatively to said board on pivot axes substantially transverse of said board for swinging movement longitudinally of the board into an extended spread position and into a retracted position against the board, a brace lever pivoted at its outer end to each of said legs on an axis substantially perpendicular to the pivot axis of said legs whereby said brace levers swing bodily with said legs, said brace levers crossing one another and pivoted to one another at the point of crossing, a pair of links pivoted at one end thereof to one another and at their opposite ends to the inner ends of said brace levers, all of said pivots being substantially parallel to the pivots between said brace levers and legs, a bracket on said board, a short link pivoted to said bracket for movement on a horizontal axis transverse of said board, a pivot member supporting the pivot between the two links, and said pivot member pivoting on said short link and with said short link relatively to said bracket for swinging said links bodily with said legs and brace levers while said links pivot relatively to one another, whereby to bring said links into a position transverse of said board with the inner ends of said brace levers in contact with the board while held by said links against transverse movement relatively to said board.
